UNITED STATES PATENT OFFICE:

CARLISLE RICKARDS, OF WILLITS, CALIFORNIA, ASSIGNOR OF ONE-HALF TO W. A. S.
FOSTER, OF WILLITS, CALIFORNIA.

EVAPORATION WATER COOLER.

Application filed June 13, 1924. Serial No. 719,781.

To all whom it may concern:

Be it known that I, CARLISLE RICKARDS, a citizen of the United States, residing at Willits, county of Mendocino, and State of California, have invented certain new and useful Improvements in Evaporation Water Coolers, of which the following is a specification.

The object of the invention is to provide a water cooler adapted to be attached by piping to a source of water supply, and to normally be completely filled with water, the cooler being so constructed and so associated with the piping that it constantly receives upon its outer surface a measured supply of water, which is evenly distributed over said surface, for evaporation and consequent cooling of the interior of the container.

The invention will be understood by reference to the accompanying drawing in which—

Figure 1 is a view in elevation of an embodiment of the invention, and

Figure 2 is a section in elevation of the same.

By reference to the drawing it will be seen that the cooler comprises a cylindrical body portion A, which is provided with a conical top portion 1 and a bottom conical portion 2, thus affording a closed receptacle for water.

In the embodiment of the invention represented in the drawing, the cooler is adapted to be supported by a small branch pipe 3 communicating with and supported by the main piping 4, the arrangement being such that water passing through the piping 4 and branch pipe 3, will pass into the cooler, from which it may be drawn via a nozzle 5.

At the top of main pipe 4 is a spigot 6, the valve of which is controlled by handle 7 and the nozzle 5 is positioned directly over the apex of conical top member 1.

Surrounding the cylindrical body portion of the cooler is an absorbent sheath 8, and

this sheath may, if desired, cover the entire cooler.

In the operation of the device, sufficient water is permitted to flow through nozzle 5 to maintain absorbent sheath 8 moist or saturated. The sheath may be of any suitable material such as burlap, preferably of coarse texture, so as to readily free the water in the evaporation of the latter. It is this evaporation which cools the water within the cooler so that the water released therefrom may be cool or cold, in accordance with the degree of the evaporation.

Inasmuch as branch pipe 3 affords a support for the cooler, the weight of the latter may be carried directly upon main pipe 4 and the cooler may thus be supported without the use of brackets, although any other desired supporting means may be employed.

The provision of the top portion 1 in the form of a cone and the arrangement of nozzle 5 is in such position that it feeds directly to the apex of the cone, insures that even distribution of the water will be effected over the conical top 1 and hence the water will be evenly fed throughout the circumference of the absorption sheath.

Having thus described my invention what I claim is new and desire to secure by Letters Patent is as follows:

A water cooler comprising a container having an intermediate cylindrical member and top and bottom conical members in water-tight connection, an outlet tube and closure at the base of said conical bottom member for the withdrawal of water from the container, a rigid short pipe communicating with the interior of the container and secured to the upper conical member and a nozzle held by said rigid short pipe in position to feed water over the apex of said conical top member.

In testimony whereof, I have signed my name to this specification.

CARLISLE RICKARDS.
